UNITED STATES PATENT OFFICE.

WILLIAM TSCHUDY, OF PORT HURON, MICHIGAN.

METHOD FOR CONTROLLING THE EFFICIENCY OF MERCURY RECTIFIERS.

14,816.

Specification of Reissued Letters Patent. Reissued Mar. 9, 1920.

Original No. 1,189,887, dated July 4, 1916, Serial No. 761,315, filed April 15, 1913. Application for reissue filed March 23, 1917. Serial No. 157,050.

To all whom it may concern:

Be it known that I, WILLIAM TSCHUDY, a citizen of the Swiss Republic, and a resident of the city of Port Huron, county of St. Clair, and State of Michigan, have invented certain new and useful Improvements in Methods for Controlling the Efficiency of Mercury Rectifiers, of which the following is a full and clear specification 10 illustrated in the annexed drawings.

The novelty of the method is more fully pointed out in the annexed claims.

My invention relates to the control of the efficiency of mercury rectifiers which, so far as I am aware, has not been controllable up to the present time.

Rectifiers of this type have heretofore been simply connected to the source of alternating current, and the rectified current 20 has been received by the current consumer such as storage batteries or the like, irrespective of the efficiency of the rectifier.

It is the object of my invention to reduce the resistance of a mercury vapor rectifier 25 to the best possible minimum by selecting a particular vapor pressure on which to operate.

My invention also comprises the method for regulating the amount of watts consumed in the compartment of a gas or vapor electric apparatus, especially of a rectifier of large capacity, by changing the pressure in the compartment through admitting or withdrawing the gaseous medium or other 35 suitable equivalent means.

It also comprises a method of changing the wave form in the compartment of a gas or vapor electric apparatus, especially of a rectifier of large capacity by varying the 40 pressure in the compartment. The improvement in the efficiency of a glass rectifier tube by regulating the pressure is approximately from 7 to 10 per cent. In case of large rectifiers where the regulation is 45 particularly important, the efficiency may be improved more than the above amount.

By my novel method which I shall describe presently it is possible to control the

efficiency of such rectifiers such that it can be easily adjusted to the maximum possible 50 efficiency.

In the accompanying drawings, Figure 1 represents diagrammatically a rectifier and its circuit connection, and Fig. 2 represents a curve diagram of the current and tension 55 curve for one period.

Referring to Fig. 1 C represents the mercury rectifier which is connected at its two anodes F and G with the two terminals A and B of an auto transformer, which in turn is connected at L_1 , L_2 with the line L from which the alternating current is supplied. The mercury cathode Q is connected by way of the direct current consuming device D with the middle terminal M of the 65 transformer. As soon as the vaporization of mercury has started current can flow in the rectifier from the anode F to the mercury cathode Q during one-half period. If now by suitable means the momentary values 70 of the potential P which exists between anode F and cathode Q, and also the momentary values of the current flowing from terminal A to the anode F are observed experimentally during an entire period T, which 75 is denoted with "T" on the abscissa "X" in Fig. 2, the form of the current and tension 80 curves is obtained, for instance as is shown in Fig. 2. As previously mentioned the time is represented by values of t along the abscissa "X" and the values of the current I and the tension P are represented by the Y ordinates. The momentary values of I and P are entered in this coördinate system during one period T. In Fig. 1 the instruments 85 by which I and P are measured are correspondingly indicated with I and P.

From the two curves in Fig. 2 it will be noted that the momentary values of the current curve I during the time period $a-b$ are 90 greater than zero; while these values are practically zero during the time period $b-c$. On the other hand the momentary values of the tension curve P are different 95 from zero during both time periods $a-b$ and $b-c$.

If now, the tension curve, which has an unsymmetrical course relatively to the time axis X, is mathematically analyzed an equation is obtained of the form:—

$$\Delta p = P_0 + P_1 \sin 2\pi nt + P_2 \sin 2.2\pi nt + P_3 \sin 3.2\pi nt \dots$$

or

$$\Delta p = P_0 + \sum P_k \sin k 2\pi nt, \text{ wherein } k = 1, 2, 3, \text{ etc.}$$

In this equation P_0 represents the constant member (direct current component) and P_k the amplitude of the several waves. Since the current curve I runs likewise 5 unsymmetrically to the time axis X its equation has the form:—

$$i = J_0 + J_1 \sin (2\pi nt - \alpha_1) + J_2 \sin (2.2\pi nt - \alpha_2) \dots$$

wherein J_0 represents the constant member (direct current component) and J_1, J_2, J_3 , etc., represent the amplitudes of the several waves and α_1 represents the difference in phase between the first tension curve and the first current curve α_2 the difference between the second tension curve and the second current curve, etc.

10 Generally the above equation may be written of the form:—

$$i = J_0 + \sum J_k \sin (k.2\pi nt - \alpha_k) \text{ wherein } k = 1, 2, 3, \text{ etc.}$$

If now one-half of the watt loss in vessel C is denoted with $\frac{E}{2}$ this loss amounts to:—

$$\frac{E}{2} = \frac{1}{T} \int_0^T i \Delta p \, dt$$

If now the values i and p as expressed by the above formulas are inserted in this equation we obtain:—

$$\begin{aligned} \frac{E}{2} &= \frac{1}{T} \int_0^T [P_0 + \sum P_k \sin k 2\pi nt] [J_0 + \sum J_k \sin (k.2\pi nt - \alpha_k)] dt \\ &= J_0 P_0 + J_1 P_1 \frac{\cos \alpha_1}{2} + J_2 P_2 \frac{\cos \alpha_2}{2} + \dots \end{aligned}$$

Thus by analyzing any of the tension and 15 current curves which may be experimentally obtained the influence of the several members of the last equation on the loss of efficiency in the vessel C may be ascertained.

From a certain current and tension curve 20 obtained by experiment as an example and by subsequently figuring the different values according to the formula for $\frac{E}{2}$ the following result was obtained:—

$$J_0 P_0 = +413,5 \quad J_1 P_1 \frac{\cos \alpha_1}{2} = -537,0$$

$$J_2 P_2 \frac{\cos \alpha_2}{2} = 65,8 \quad J_3 P_3 \frac{\cos \alpha_3}{2} = 7,8$$

From this example it may be seen that the 25 loss of efficiency in vessel C depends largely upon the curve form, since even the fourth member of the equation (not obtained here) has an effect on the amount of loss in efficiency.

30 I have now determined by experiment that the curve form depends upon the gas pressure in vessel C. Thus also the loss of efficiency depends upon the pressure in the vessel.

If now, according to the results thus obtained the pressure in vessel C is suitably varied the tension and current curve and simultaneously the efficiency of the rectifier can be varied. The variation of gas pressure may be brought about for instance by 35 pumping a gaseous medium into the vessel C, or by withdrawing it therefrom as the case may be, by means of a pump N or other suitable equivalent means. Thus it is possible to adjust the loss in such rectifiers 40 to a minimum by varying the gas pressure in the rectifier. The consumption of energy is preferably determined by a wattmeter in the usual well-known manner.

The adjustment of the efficiency loss may 50 be of great value if the apparatus is for instance connected to a source of alternating current, the curve form of which is very unfavorable with regard to the efficiency loss; thus by subsequently regulating the 55 vacuum in the rectifier tube the curve form of the tension and the current may be influenced in such manner that the loss in efficiency is a minimum. For instance, in case of a very sharp peak curve of the source of 60 energy the consumed energy of the tube may amount to 210 watts, while in case of a sine

curve at the same tension and the same load and otherwise under the same conditions, the consumed energy may only amount to 138 watts.

5 I claim:

1. The method of controlling the wave form transmitted by a mercury vapor apparatus which consists in changing the physical condition of the vapor in said apparatus.

10 2. The method of controlling the wave form transmitted by a mercury vapor apparatus which consists in varying the pressure or density of the vapor of said apparatus.

15 3. The method of controlling the efficiency of vapor rectifiers which consists in supplying a varying current flow to the rectifier and varying its form factor by varying the

pressure or density of the vapor of the rectifier. 20

4. The method of controlling the efficiency of vapor rectifiers receiving alternating currents, which consists in increasing or decreasing the pressure or density of the vapor 25 for the particular current or load being employed, to reduce resistance in the rectifier to a minimum and regulate the watts consumed with said current and load.

5. The method of controlling the rectified 30 current of vapor rectifiers, which consists in delivering an alternating current flow to the rectifier and varying its anode current by increasing or decreasing the pressure or density of the vapor, thereby varying the 35 watts consumed in the rectifier.

WILLIAM TSCHUDY.
